Henry T. Romeritz

UNITED STATES PATENT OFFICE.

HENRY T. ROMERTZE, OF PHILADELPHIA, PENNSYLVANIA.

AUTOMATIC CAR-COUPING.

Specification of Letters Patent No. 34,284, dated January 28, 1862.

To all whom it may concern:

Be it known that I, HENRY T. ROMERTZE, of Philadelphia, in the county of Philadelphia, in the State of Pennsylvania, have invented a new Improved Automatic Car-Coupling; and I do hereby declare that the following is a full and exact description thereof, reference being had to the accompanying drawings and to the letters of reference marked thereon.

The nature of my invention consists that Figure 1 is a box *a*, wherein are two jaws *b*, *b* the rear end of which, *m*, *m*, move in the sockets *c*, *c*, a lever *d*, rotating obliquely on a pin *e* between the said jaws, a bar *f*, a wire spring *g*, and two projections *h*, *h*, secured on each side.

The mode of operating the said automatic car-coupling is effected by pulling in Fig. 2 the lever *d* toward the rear end of the box *p*. The two jaws *b*, *b*, are thereby forced to the side of the box *q*, *q*, at which time the projections *h*, *h*, by entering in Figs. 3 and 4 the jaw slots *i*, *i* expel the parallel barhead ends *l*, *l*, from the said slots, and thus assist the bar *f* to issue freely from the box, respective car buffer; again by pushing in Fig. 1 the lever *d* to the front end of the box *r*, the two jaws *b*, *b*, will close together, its end appearing *b*, *b*, in Fig. 5, when by pushing the barhead end *k*, between the said jaws they will just so much open as to admit the whole barhead, of which the parallel ends *l*, *l*, enter the jaw slots *i*, *i*, which at once

resumes its closed form, the lower jaw being held in that position by the spring *g*, and the upper jaw by the lever *d*, by all of which the bar *f*, is held firmly between the said jaws, which last are doubly securely held in their position, first, because the rear ends of the jaws *m*, *m*, by being inserted in the sockets *c*, *c*, resist the pulling force of the bar, end, secondly, because the front jaws ends *n*, *n*, reach close to the inside box front *o*, the latter assists the jaws to maintain their position.

I construct the coupling bar of the form as represented in the drawings, and arrange that the entire length of the same must be a fraction shorter, yet twice the distance of that part of the car buffer beginning from the right side of the lever *s* as showing in Fig. 6, to the outside carbuffer front *t*, in consequence of which the bending or breaking of the said bar while in the process of coupling is rendered impossible.

I claim as my invention and desire to secure by Letters Patent,

The jaws *b*, *b*, the sockets *c*, *c*, the slots *i*, *i*, in combination with the releasing lever *d*, spring *g*, case or box *a*, with the projections *h*, *h*, substantially as shown and described.

HENRY T. ROMERTZE.
